Stanley Sauvage

UNITED STATES PATENT OFFICE

2,007,877

ELECTRIC HEATING UNIT FOR FOOD COOKERS

Stanley Sauvage, Chicago, Ill.

Application May 5, 1934, Serial No. 724,682

12 Claims. (Cl. 219—37)

This invention relates to electric heating elements for cooking apparatus of the type disclosed in my co-pending application, Serial Number 667,393, filed April 22, 1933, and is in part a 5 division of the said application.

It has been found that the ceramic body of the heating unit absorbs considerable heat from the coils or resistance elements, with the result that considerable time is necessary to produce 10 the temperature desired, with a consequent consumption of current, as well as considerable loss in current.

It is one of the objects of the present invention to reduce the current consumption by providing 15 in heating units of this character improved means for supporting or holding the coil or element spaced from, or out of contact with the walls or face of the body unit, with the result that only a minimum amount of heat will be absorbed 20 by the body portion, and thereby facilitate the heating or raising of the temperature within the cooking apparatus.

To the attainment of these ends and the accomplishment of other new and useful objects as 25 will appear, the invention consists in the features of novelty in substantially the construction, combination and arrangement of the several parts hereinafter more fully described and claimed, and shown in the accompanying drawing illustrating this invention, and in which

Figure 1 is a top plan view of a heating unit of this character, constructed in accordance with the principles of this invention, with parts broken away.

Figure 2 is a detail sectional view, taken on line 2—2, Figure 1, on an enlarged scale.

Figure 3 is a detail sectional view, taken on line 3—3, Figure 2.

The heating unit consists essentially of a disc 40 or body of ceramic or like heat resisting insulating material 10, and the body is preferably of annular construction and formed by a plurality of arc shaped sections arranged end to end. Each of the sections may be provided with 45 an ear or lug 11 adjacent the inner face and through which fastening screws or bolts 12 pass, for the purpose of anchoring the element and the sections in assembled relation.

The body thus formed is provided with a plurality of annular open seats 13—14 concentrically arranged, and the seats are continuous and may be of any desired depth and width.

Arranged within each of the seats and spaced 55 in directions lengthwise of the respective seats are lugs or projections 15 which are formed integral with the inner face of the innermost wall of the seats. These lugs or projections may be of any desired thickness and width and are also shaped to form portions 16 integral with the bottoms of the seats.

The numeral 17 designates a heating coil or resistance element which is seated in each of the seats 13—14, and the coils are of a diameter considerably less than the depth and width of each of the respective seats. The ends of the coils may be connected at one end as at 18 and to which connection is secured one end of a service wire. 5

The numerals 19 and 20 designate binding posts at the other ends of the coil to which conductors are connected. 10

When the coils are inserted in the respective seats 13 and 14 they will be placed under tension causing the coils to expand slightly and this tension will cause portions of the coils to contact with the lugs or projections 15 on the inner 15 face of the seats and the portions of the lugs or projections 15 at the bottom of the seats will form supports for the coils.

With this construction it will be manifest that the greater portion of the coils will be held out 20 of contact with the inner face of the wall of the seat as well as above the bottom of the seats so as to form spaces between the coils and the faces of the walls of the seats. This will insure a minimum amount of absorption of the heat 25 units by the walls of the seats, and necessitate only a minimum amount of current to heat the coils to the desired temperature.

Ventilating openings 21, any number of which may be provided, extend through the body member 10 and register with the respective seats 13—14 so as to permit of a circulation of air around the coils. 30

Lugs or projections 22 may be provided on the top of the walls of the seats to project over the 35 top of the coils and thereby hold the coils from accidental displacement from the seats.

Portions of the upper face of the body may be cut away, if desired, as at 23, and portions may be cut away as at 24, on the bottom of the 40 elements, for the purpose of lightness and also to assist in the circulation of air with respect to the elements.

The body portion is constructed in sections for 45 manufacturing purposes, so as to facilitate and reduce the cost of manufacture, and also to necessitate a minimum amount of space when the ceramic body portion is being baked in the oven as the arc shaped sections will permit of a nesting in the oven. At the same time a minimum 50 amount of space will only be required for shipping purposes.

While the preferred form of the invention has been herein shown and described, it is to be 55 understood that various changes may be made in the details of construction and in the combination and arrangement of the several parts, within the scope of the claims, without departing from the spirit of this invention.

What is claimed as new is:—

1. An electric heating unit of annular configuration, the opening in said unit being of a substantial diameter, said unit comprising an insulating body having open substantially parallel annular seats, exposed heating coils seated in said seats, means formed in said seats and spaced throughout the length of the coils for holding the coils out of contact with the walls of said seats, said body being of sectional construction, and an integral projecting lug formed on each of said sections and projecting into said opening, there being an opening in said lug for the reception of an anchor element.
- 15 2. An electric heating unit comprising an insulating body having open annular seats, projections on the inner face of the innermost wall of said seats and spaced in directions lengthwise of the seats, and a heating coil seated in each of the seats, said coils being maintained under tension to cause them to contact and remain in contact with said projections, whereby extended portions of the coils will be maintained out of contact with and spaced from the inner face of the innermost wall of said seats.
- 20 3. An electric heating unit comprising an insulating body having open annular seats, projections on the inner face of the innermost wall and on the bottom of said seats and spaced in directions lengthwise of said seats, and a heating coil in and extending throughout substantially the length of each of said seats, said coils being maintained under tension and in contact with said projections, whereby the remaining portions of the coils will be held spaced from the face of the wall and bottom of said seats.
- 25 4. An electric heating unit comprising an insulating body having open annular seats, projections on the inner face of the innermost wall and on the bottom of said seats and spaced in directions lengthwise of said seats, and a heating coil in and extending throughout substantially the length of each of said seats, said coils being maintained under tension and in contact with said projections, whereby the remaining portions of the coils will be held spaced from the face of the wall and bottom of said seats, there being ventilating openings through said body and registering with said seats.
- 30 5. An electric heating unit comprising an insulating body having open annular seats, projections on the inner face of the innermost wall and on the bottom of said seats and spaced in directions lengthwise of said seats, and a heating coil in and extending throughout substantially the length of each of said seats, said coils being maintained under tension and in contact with said projections, whereby the remaining portions of the coils will be held spaced from the face of the wall and bottom of said seats, said body being formed of a plurality of arc shaped sections arranged end to end.
- 35 6. An electric heating unit comprising an insulating body having open annular seats, projections on the inner face of the innermost wall and on the bottom of said seats and spaced in directions lengthwise of said seats, a heating coil in and extending throughout substantially the length of each of said seats, said coils being maintained under tension and in contact with said projections, whereby the remaining portions of the coils will be held spaced from the face of the wall and bottom of said seats, said body
- being formed of a plurality of separate arc shaped sections arranged end to end, and means for anchoring said sections.
7. An electric heating unit comprising an annular insulating body having one or more open annular seats, exposed heating coils seated in said seats and extending substantially throughout the length of said seats, said body being formed of a plurality of arc shaped sections arranged end to end, and an integral projecting lug projecting from the face of each of said sections and disposed beyond the side of said seat, there being an opening through said lug for the reception of an anchoring element.
- 10 8. An electric heating unit comprising an annular insulating body having open and substantially parallel annular seats, exposed heating coils seated in said seats and extending substantially throughout the length of said seats, said body being formed of a plurality of arc shaped sections arranged end to end, the seats in each section being substantially parallel, and formed integral with the sections, and projecting from the inner face thereof and disposed within the opening formed by said unit for the reception of an anchoring device.
- 15 9. As an article of manufacture for use in an annular sectional heating unit body, a segmental member having an open seat for the reception of a heating coil, said seat extending in a direction lengthwise of the member and substantially throughout the length thereof, and an anchoring lug integral with and projecting laterally beyond the outer face of one of the walls of the segment.
- 20 10. As an article of manufacture for use in an annular sectional heating unit body, a segmental member having a plurality of open seats for the reception of heating coils, said seats being substantially parallel and extending in a direction lengthwise of the member and substantially throughout the length thereof, and an anchoring lug integral with and projecting laterally beyond the outer face of one of the walls of the segment.
- 25 11. As an article of manufacture for use in an annular sectional heating unit body, a segmental member having an open seat for the reception of a heating coil, said seat extending in a direction lengthwise of the member and substantially throughout the length thereof, an anchoring lug integral with and projecting laterally beyond the outer face of one of the walls of the segment, and projections on the inner face of the innermost wall and spaced in directions lengthwise of said seat for holding portions of a heating coil that is disposed within the seat, spaced from the face of the wall.
- 30 12. As an article of manufacture for use in an annular sectional heating unit body, a segmental member having an open seat for the reception of a heating coil, said seat extending in a direction lengthwise of the member and substantially throughout the length thereof, an anchoring lug integral with and projecting laterally beyond the outer face of one of the walls of the segment, and projections on the inner face of the innermost wall and on the bottom of the seat and spaced in directions lengthwise of said seat for holding portions of a heating coil that is disposed in the seat, spaced from the face of the wall and from the bottom of the seat.

STANLEY SAUVAGE.
